(57) **CLAIM**

The ornamental design for a vacuum cleaner, as shown and described.

DESCRIPTION

1. Vacuum cleaner
- 1.1 Front view of the vacuum cleaner of our present design;
- 1.2 Rear view of the vacuum cleaner of our present design;
- 1.3 Left side view of the vacuum cleaner of our present design;
- 1.4 Right side view of the vacuum cleaner of our present design;
- 1.5 Top view of the vacuum cleaner of our present design;
- 1.6 Bottom view of the vacuum cleaner of our present design;
- 1.7 Left front perspective view of the vacuum cleaner of our present design; and
- 1.8 Bottom rear perspective view of the vacuum cleaner of our present design.

1 Claim, 8 Drawing Sheets(56)
